ANALGESIC CYCLOBUTANES

Samuel Kuna, Westfield, and Anthony W. Pircio, East Brunswick, N.J., assignors to Bristol-Myers Company, New York, N.Y., a corporation of Delaware
No Drawing. Filed Nov. 25, 1959, Ser. No. 855,285
26 Claims. (Cl. 167—65)

This invention relates to therapeutic compositions. More specifically, this invention relates to compositions which possess analgesic activity and which show indications of antihallucinatory and anticonvulsive activity.

In the past a large number of substances have been used to produce analgesic action. All of the prior art analgesics have suffered from one or more serious disadvantages. Some of the substances employed are strong narcotic or toxic agents and give rise to addiction or deleterious side effects such as respiratory depression, pruritis, constipation, nausea, sphincter constriction, sedation and euphoria. Others are only slightly effective and give no relief against deep-seated and pronounced pain. Still others are absorbed only slowly from the alimentary canal and require a prolonged period and large dosages before their action is effective. Still other substances require an aryl substituent in the molecule and give irritation on parenteral injection or have a low therapeutic ratio.

It has now been found that excellent analgesic activity is obtained by the administration of cyclobutane derivatives wherein one carbon atom of the cyclobutane ring is substituted by two lower alkyl radicals, a second ring carbon atom has one of its valences satisfied by a tertiary amine and the remaining valence of the second carbon atom is satisfied by hydrogen or a lower alkyl radical and wherein at least one of the third and fourth carbon atoms of the cyclobutane ring contains at least one electro-negative group as hereinafter disclosed with the remaining valences of the third and fourth ring carbon atoms being satisfied by hydrogen or lower alkyl radicals.

The cyclobutane derivatives of this invention possess many advantageous properties when used as analgesics. Although some of the advantageous analgesic properties of the active ingredients are dependent on the particular compound selected, the advantageous analgesic properties include: greater therapeutic effect than known non-prescriptive types of analgesics such as aspirin, phenacetin or salicylamide; absence of deleterious side effects, e.g., respiratory depression, vomiting, constipation, sedation, euphoria and pruritis as are produced by narcotic types of analgesics; good tolerance and less toxicity than many other analgesics presently available; a more favorable therapeutic ratio than codeine; absence of irritation on parenteral injection; the attainment of a maximum analgesic potency value with relatively small quantities of the analgesic wherein the potency value is not significantly increased by the administration of larger quantities; good analgesic effect even when the molecule of the active compounds does not contain the usual aromatic constituents; no physical dependency upon withdrawal; rapid absorption from the alimentary canal and a rapid analgesic effect. Illustratively, diethyl 3,3-dimethyl-4-dimethylaminocyclobutane-1,2-dicarboxylate·HCl; one of the compounds of this invention is relatively non-toxic (e.g. LD 50 of oral dosages of about 3000 mg./kg. of animal weight in mice, greater than 12,000 mg./kg. of animal weight in rats and greater than 3000 mg./kg. of animal weight in rabbits, cats and dogs); has a very favorable therapeutic ratio, e.g., better than that of codeine; exhibits synergistic analgesic effects with conventional analgesics containing an aromatic ring, e.g., aspirin, morphine etc.; is not antagonized by Nalline (N-allyl normorphine) but gives an increased analgesic effect with Nalline; gives no physical dependence upon withdrawal; shows

2

no deleterious side effects; shows no apparent cumulative toxicity; produces analgesia in the range of the less potent narcotics such as codeine and 2-propionoxy-4-dimethylamino-1,2-diphenyl-3-methylbutane hydrochloride; shows an absence of respiratory depression and in fact this compound stimulates respiration; permits the attainment of a level of analgesia which is not significantly increased by the administration of larger dosages and the animals treated with the compound show very rapid recovery from toxic signs exhibited following administration of large dosages. Illustrative of specific advantageous properties for methyl 3,3-dimethyl-2-dimethylaminocyclobutane-1-carboxylate, another active compound of this invention, there can be mentioned; low toxicity (even more favorable than that of the above discussed diester compound); a very favorable therapeutic ratio (e.g. better than that of codeine); an absence of antagonism by Nalline; no apparent cumulative toxicity; analgesia in the potency range of the less active narcotics such as codeine and 2-propionoxy-4-dimethylamino-1,2-diphenyl-3-methylbutane hydrochloride; no deleterious side effects; an absence of physical dependence upon withdrawal; an absence of respiratory depression and in fact an increase in respiration; and the animals treated with this compound show a very rapid recovery from toxic signs exhibited following administration of large dosages. This mono-ester compound gives very much of a straight line dose response, providing increased analgesic activity on increased dosage levels, particularly dosage levels above 100 mg./kg., whereas the diester compound reaches a peak of activity at a dosage level of about 100 mg./kg. and the activity is not significantly increased by larger dosage levels above that amount.

A preferred class of the analgesically active cyclobutane derivatives can be represented by the following generic formula:

wherein A is a lower alkyl radical; A' is a lower alkyl radical; R is hydrogen, an electronegative radical as hereinafter disclosed or a lower alkyl radical; R¹ is hydrogen, a lower alkyl radical or an electronegative radical as hereinafter disclosed; R² is hydrogen, an electronegative radical as hereinafter disclosed or a lower alkyl radical; R³ is hydrogen, a lower alkyl radical or an electronegative radical as hereinafter disclosed; provided that at least one of R, R¹, R² or R³ is an electronegative radical as hereinafter disclosed; X is a tertiary amine radical and R⁴ is hydrogen or a lower alkyl radical. By the terms lower alkyl radical or lower alkyl group we mean an alkyl radical containing from 1 to 6 carbon atoms, e.g., methyl, ethyl, propyl, isopropyl, butyl, tertiary butyl, etc. The lower alkyls having from 1 to 2 carbon atoms are preferred. By the term tertiary amine radical we mean a radical of the ammonia molecule wherein the hydrogen atoms have been replaced by three radicals. The tertiary amine can be a lower alkyl amine, cycloaliphatic amine, an aryl amine or a saturated cyclic amine wherein the ring contains elements such as sulfur or oxygen in addition to nitrogen and carbon. Illustrative of amine radicals there can be mentioned: those of lower alkyls, e.g., dimethyl, diethyl, dipropyl, diisopropyl, diisobutyl, methyl ethyl amine, methylisopropylamine, ethyl tertiarybutylamine and the like; cyclic amines including substituted alicyclic amines, e.g., piperazino, piperidino, morpholino, thiomorpholino and the like. It is preferred that the amine be a dialkyl amine having from 1 to 2 carbon atoms in each alkyl radical and that the nitrogen be bound directly to a ring carbon atoms of the cyclobutane. The electro-

negative radicals or groups satisfactory in the compounds of this invention are: phenyl and substituted phenyls, nitro, lower alkyl sulfonyl, cyano, lower alkyl esters, and lower alkyleneamino radicals. However, the compound is inactive if the group is capable of dissociation into two fragments, one carrying a formal negative charge attached to the cyclobutane ring and a free positive fragment. Illustrative of the sulfonyl radical ($-\text{SO}_2-\text{R}$) there can be mentioned: methyl sulfonyl, ethyl sulfonyl, propyl sulfonyl, isopropyl sulfonyl, butyl sulfonyl, isobutyl sulfonyl and the like. Illustrative of ester groups

there can be mentioned: the carbomethoxy, carboethoxy, carbopropoxy, carboisopropoxy, carbobutoxy, carboisobutoxy and the like. It is preferred that the alkyl portion of the carbalkoxy radical be one having from 1 to 3 carbon atoms. In addition to the esters formed by the reaction of a carboxylic acid of cyclobutane with a lower alkyl alcohol it has been found that the reduction of a cyclobutane carboxylic acid to a cyclobutyl methyl alcohol and subsequent reaction of the alcohol with a lower alkyl acid also produces a therapeutically active and equivalent compound. Illustrative of such esters formed from a cyclobutyl methyl alcohol and a lower alkyl acid there can be mentioned those wherein the following radicals are attached directly to one of the ring carbons:

and

The more preferred analgesically active compounds of this invention can be represented by the following generic formula:

wherein A, A', R¹, R² and X are the same radicals as discussed for the preferred generic formula and provided that at least one of R¹ and R² is an electronegative group as hereinabove disclosed. The preferred electronegative group is that of lower alkyl carbalkoxy radicals particularly when the alkyl contains from 1 to 3 carbon atoms. It is also preferred that when only one of R¹ and R² is an electronegative group that the remaining R¹ and R² be hydrogen.

Either the cyclobutane derivatives of this invention or their acid addition salts can be administered by the conventional methods, the conventional types of unit dosages or with the conventional pharmaceutical carriers to produce an analgesic effect in human beings and animals. Conventional methods of administration of the analgesics include oral or parenteral administration. Oral administration by the use of tablets or capsules or in liquid form such as suspensions, solutions or emulsions is particularly advantageous since the novel analgesics are rapidly absorbed from the gastrointestinal tract. When formed into tablets, the conventional binding and disintegrating agents used in analgesic unit dosages can be used. Illustrative of binding agents there can be mentioned: glucose, gum acacia, gelatin and starch paste. Illustrative of disintegrating agents there can be mentioned: corn starch, keratin and potato starch. When administered as liquids the conventional liquid carriers can be used.

The acid addition salts are formed by the conventional techniques of neutralizing the amine portion of a compound with either an organic or inorganic acid. Illustra-

trative of the acids there can be mentioned: hydrochloric, sulfuric, citric, acetic, malonic, maleic and phosphoric acids. The novel analgesic compounds of this invention can be administered in combination with other analgesics particularly those containing an aromatic nucleus. Such combination of some of the novel analgesic compounds with an aromatic nucleus analgesic can produce a synergistic analgesic effect. Illustrative of analgesics containing an aromatic nucleus which produce synergistic effects with the cyclobutane derivatives there can be mentioned: aspirin and its salts such as those of the alkali metal or alkaline earth metal salts, e.g., sodium, potassium, calcium and magnesium; D-propoxyphene-HCl, codeine phosphate and morphine sulfate.

The unit dosage or analgesically effective quantity of the cyclobutane derivatives for human beings can vary over wide limits such as that of about 0.1 of a grain to about 25 grains or more such as 100 grains. The upper limit is limited only by the degree of effect desired and economic considerations. For oral administration it is preferable to employ from about 1 to about 10 grains per unit dosage. When administered parenterally, it is preferable to employ about 0.10 to about 2 grains. Each unit dosage form of the novel therapeutic compounds can contain from about 1% to about 95% and preferably from about 5% to 80% of the novel analgesic agent by weight of the entire composition with the remainder comprising conventional pharmaceutical carriers and optionally other analgesics such as aspirin. By the term pharmaceutical carrier we intend to include non-analgesic materials which are conventionally used with analgesics and includes fillers, diluents, binders, lubricants, disintegrating agents and solvents. When it is desired to use the novel analgesics in combination with a conventional analgesic containing an aromatic nucleus, the quantity of the conventional aromatic analgesic used in combination with the cyclobutane derivative is not critical and can vary from 0.05 to 10 times the weight of novel analgesic employed depending on the conventional analgesic employed. Thus with aspirin it is preferable to use between about .25 to about 4 times the weight of the novel analgesic. Of course, it is possible to administer the novel analgesics, e.g., the pure compounds or their acid addition salts, without the use of a pharmaceutical carrier.

EXAMPLE A

A suitable formulation of tablets consists of:

	Grams
(1) The citric acid salt of diethyl 3,3-dimethyl-4-dimethylaminocyclobutane-1,2-dicarboxylate	12.5
(2) Lactose	30
(3) Starch	5
(4) Magnesium stearate	2

The citric acid salt of diethyl 3,3-dimethyl-4-dimethylamino-cyclobutane-1,2-dicarboxylate, lactose, and starch are thoroughly mixed and granulated. For tabletting, the magnesium stearate is added, mixed with the granules, and the mixture tableted on a rotary press. Use of this procedure produces 100 tablets each containing 125 mg. of the active analgesic salt.

EXAMPLE B

Another suitable formulation of tablets consists of:

	Grams
(1) The hydrochloride salt of methyl 3,3-dimethyl-2-dimethylaminocyclobutane-1-carboxylate	25
(2) Mannitol	60
(3) Starch	10
(4) Magnesium stearate	4

The hydrochloride salt of methyl 3,3-dimethyl-2-dimethylamino-cyclobutane-1-carboxylate, mannitol and starch are thoroughly mixed and granulated. For tablet-

7

8

In addition to the above illustrated compounds the following can also be mentioned:

2-dimethylamino-3,3-dimethyl-1-methyl-1-carbmethoxycyclobutane;
 2-dipropylamino-3,3-dimethyl-4-methyl-4-carbethoxy-1-methyl-1-carbethoxycyclobutane;
 2,2-diethyl-3-piperidinocyclobutylmethyamine;
 2-dimethylamino-3,3-dimethyl-4-ethyleneamino-1-carbethoxycyclobutane;
 tetramethyl-4,4-dimethyl-3-dimethylaminocyclobutane-1,1,2,2-tetracarboxylate;
 and the like.

EXAMPLE 1

This example shows analgesic effect on rats by the tail flick test. This test is performed by uniformly blackening the tails of rats, administering an analgesic to the animal and subsequently focusing a beam of light on the animal's tail at various intervals after administration of the analgesic. The time required for the animal to flick its tail after the beam of light is applied determines the analgesic effect of the material being tested. The longer the interval for the tail flick, after the application of the concentrated beam of light, the more effective is the analgesic. Predetermined dosages of diethyl 3,3-dimethyl-4-dimethylaminocyclobutane-1,2-dicarboxylate·HCl, D-propoxyphene·HCl and the very strong narcotic types of analgesics such as morphine sulfate and codeine phosphate were given to rats. Each material was administered orally to sets of fifteen animals except for morphine sulfate which was given subcutaneously to fifteen animals and codeine phosphate which was given orally to twenty-five animals. The following quantities of each material were used: morphine sulfate, 1.5 milligrams per kilogram weight of each animal; D-propoxyphene·HCl, 25 milligrams per kilogram weight of each animal; codeine

phosphate, 40 milligrams per kilogram weight of each animal; and diethyl 3,3-dimethyl-4-dimethylaminocyclobutane-1,2-dicarboxylate·HCl, 100 milligrams per kilogram weight of each animal. The time in seconds during which the animals could tolerate the concentrated beam of light at various intervals after administration of the analgesics is given in Table 1. The values in the table are averages for the animals in each set.

Table 1

Time in minutes after administration of analgesic	20	40	60
Time in seconds for pain response of animals treated with:			
Morphine sulfate	14.3	5.8	6.0
D-propoxyphene·HCl	14.3	5.7	5.9
Codeine phosphate	14.3	5.8	5.6
Diethyl 3,3-dimethyl-4-dimethylaminocyclobutane-1,2-dicarboxylate·HCl	14.3	5.7	5.4
			4.9

¹ Immediately prior to administration of analgesic.

Table 1 shows that an oral dose of 100 mg. of the cyclobutane compound per kg. weight of the animal is equivalent in analgesic potency to oral doses of either 25 mg./kg. of D-propoxyphene·HCl or 40 mg./kg. of codeine phosphate and to a subcutaneous dose of 1.5 mg./kg. of morphine sulfate.

EXAMPLE 2

This example shows the analgesic dose response of diethyl 3,3-dimethyl-4-dimethylaminocyclobutane-1,2-dicarboxylate·HCl on rats by the tail flick method as described in Example 1. The cyclobutane compound was administered orally to all the animals. Four different dosages were used wherein 350 milligrams per kilogram weight of animal was administered to five rats; 175 milligrams per kilogram weight of animal was administered to fifteen rats; 100 milligrams per kilogram weight of animal was administered to fifteen rats; and twenty-five additional rats were administered 50 milligrams per kilogram weight of animal. The time required for the rats to flick their tails after the concentrated beam of light was focused thereon at various intervals of time is given in Table 2. Average readings for the animals of each dosage group is also given in the table.

Table 2

Time in minutes after administration of analgesic	20	40	60
Time required in seconds for pain response of animals tested with the following quantities of diethyl 3,3-dimethyl-4-dimethylaminocyclobutane-1,2-dicarboxylate·HCl:			
350 mg. per kg.	14.3	5.9	5.9
175 mg. per kg.	14.3	5.8	5.5
100 mg. per kg.	14.3	5.8	5.3
50 mg. per kg.	14.3	5.3	5.0
			4.9

¹ Immediately prior to administration of analgesic.

It can be seen from Table 2 that large quantities of the cyclobutane compound do not give a proportionally high analgesic effect and that above certain quantities the increase in analgesic effect is not significant but the duration of activity is somewhat increased.

EXAMPLE 3

This example shows potentiation of diethyl 3,3-dimethyl-4-dimethylaminocyclobutane-1,2-dicarboxylate·HCl with Nalline and the antagonistic effect of Nalline with morphine sulfate. The rat tail flick test as described in Example 1 was employed. Two sets of five rats in each set were given 175 mg. of diethyl 3,3-dimethyl-4-dimethylaminocyclobutane-1,2-dicarboxylate·HCl per kg. of animal weight. Two sets of five rats in each set were subcutaneously injected with 2 mg. of morphine sulfate per kg. weight of each animal. Tail flick determinations were made for 20 minutes after administration of the two analgesics after which 1 mg.

of Nalline per kg. weight of each animal was subcutaneously administered to the rats of one set which had been treated with morphine sulfate and one set which had been treated with diethyl 3,3-dimethyl-4-dimethylaminocyclobutane-1,2-dicarboxylate·HCl. The results of this test are shown in Table 3 wherein the average time for a tail flick is reported in seconds for each group.

Table 3

Time in minutes after administration of analgesic	20	40	60
Time required for pain response of animals:			
Morphine sulfate	14.3	6.1	6.5
Morphine sulfate plus addition of Nalline after 20 minutes	14.3	6.0	5.0
Diethyl 3,3-dimethyl-4-dimethylaminocyclobutane-1,2-dicarboxylate·HCl	14.3	5.8	5.5
Diethyl 3,3-dimethyl-4-dimethylaminocyclobutane-1,2-dicarboxylate·HCl plus addition of Nalline after 20 minutes	14.3	5.9	6.5

¹ Immediately prior to administration of analgesic.

It can be seen from the Table 3 that the addition of Nalline caused a potentiation of diethyl 3,3-dimethyl-4-dimethylaminocyclobutane-1,2-dicarboxylate·HCl whereas it antagonized the morphine sulfate.

EXAMPLE 4

This example shows that diethyl 3,3-dimethyl-4-dimethylaminocyclobutane-1,2-dicarboxylate hydrochloride is non-irritating on parenteral injection. Intradermal skin irritation tests were conducted on rabbits using the Trypan Blue method. Concentrations of 1.0%, 5.0% and 10.0% of the HCl salt of the diethyl ester were injected intradermally in a volume of 0.3 cc. A different skin area was used for each concentration. A control area was treated with a similar volume of physiological saline.

Immediately following the injection of the test drug, 1.0 cc. of a 1.0% solution of Trypan Blue per kilogram was administered intravenously. Observations were made for the degree of localization of the dye at 3, 24, 48 and 160 hours after drug treatment. No signs of accumulation of dye were evident in those areas treated with 1.0% of the drug or saline. Definite localization of dye was noted at the areas treated with 5.0% and 10.0% of diethyl 3,3-dimethyl-4-dimethylaminocyclobutane-1,2-dicarboxylate·HCl. The dye had practically disappeared within 48 hours from the area treated with the 5.0% concentration, while some dye was still evident in the area treated with the 10.0% concentration. No signs of erythema, edema or other gross evidence of irritation were noted during the 160 hour treatment period.

EXAMPLE 5

This example shows the quantity of diethyl 3,3-dimethyl-4-dimethylaminocyclobutane-1,2-dicarboxylate·HCl required for an LD₅₀ in mice by different methods of administration.

Acute intravenous ----- LD₅₀=125 mg./kg. of animal (5 mice per dose level for a total of 25 animals).
 Acute intraperitoneal --- LD₅₀=700 mg./kg. of animal (10 mice per dose level for a total of 60 animals).
 Acute subcutaneous --- LD₅₀=>2,000 mg./kg. of animal (10 mice per dose level for a total of 20 animals).
 Acute oral ----- LD₅₀=3,000 mg./kg. of animal (10 mice per dose level for a total of 50 animals).

It can be seen that diethyl 3,3-dimethyl-4-dimethylaminocyclobutane-1,2-dicarboxylate·HCl has a relatively low order of toxicity.

11
EXAMPLE 6

This example shows subacute administration of diethyl 3,3 - dimethyl - 4 - dimethylaminocyclobutane - 1,2-dicarboxylate·HCl to rats for a period of three weeks. Daily oral administrations (6 times weekly) of the cyclobutane compound at dosage levels of 100, 300 and 500 mg./kg. were given to young rats for a period of three weeks. Since a limited amount of material was available for these tests, only males received the 500 mg. level. Five animals of each sex were used on each dose level tested. No untoward effects or signs of toxicity were evident during this treatment period. On the basis of appetite, body weight, appearance and behavior, the treatment was well tolerated by all animals. Average body weights of males and females at each dose level during the conduction of the test are given in Table 4. All of the animals including the controls were of about the same age.

Table 4
SUBACUTE TOXICITY
[Rat weights in grams]

	Number of rats	Original weight	First week	Second week	Third week
Male:					
100 mg./kg.	5	132.0	167.0	198.6	233.2
300 mg./kg.	5	138.8	178.0	208.8	243.6
500 mg./kg.	5	139.2	182.4	217.0	234.2
Controls	5	133.2	171.4	199.6	226.4
Females:					
100 mg./kg.	5	119.6	155.8	177.2	194.6
300 mg./kg.	5	120.2	146.8	166.2	179.0
Controls	5	117.0	144.2	167.2	183.0

EXAMPLE 7

Similar to the studies in rats, daily doses of 100 and 300 mg. of diethyl 3,3-dimethyl-4-dimethylaminocyclobutane-1,2-dicarboxylate·HCl were administered orally per kilogram (6 times weekly) to mature male dogs for a period of three weeks. Two animals were used to test each dose level. No untoward side effects such as vomiting or anorexia were evident in this study. Individual body weights of the experimental animals at each dose level are shown in Table 5.

Table 5
[Body weight of dogs in kg.]

Dog No.	Dose mg./kg.	Original weight	First week	Second week	Third week
20		11.2	11.3	11.7	11.8
21		9.9	10.1	10.7	10.8
22	100	12.7	12.5	12.9	12.8
23	100	11.1	10.8	11.3	11.1
24	300	9.8	9.1	9.5	9.6
25	300	11.6	11.5	11.0	10.9

EXAMPLE 8

This example shows analgesic tests on rats by the tail flick test as described in Example 1. Predetermined dosages of methyl 3,3-dimethyl-4-dimethylaminocyclobutane-1-carboxylate·HCl were administered orally to rats. Each dosage level contained five animals and the results are given in Table 6 as the average time in seconds for the pain response of the animals in each dosage level.

Table 6

Time in minutes after administration of analgesic		20	40	60
Time required in seconds for pain response of animals tested with the following quantities of methyl 3,3-dimethyl-2-dimethylaminocyclobutane-1-carboxylate·HCl:				
100 mg. per kg.	1	4.2	5.5	5.7
175 mg. per kg.	2	4.2	6.4	5.5
	3			
	4

	6			
	7			
	8			
	9			
	Aspirin			
	Codeine			

¹ Immediately prior to administration of analgesic.

It can be seen from Table 6 that the test compound of Example 8 possesses analgesic activity.

12
EXAMPLE 9

This example shows analgesic tests on rats by the tail flick test as described in Example 1. Predetermined dosages of methyl 2,2-dimethyl-3-(1-piperidyl)cyclobutane-1-carboxylate·HCl were administered orally to rats. Five animals were used with each dosage level. The results are given in Table 7 as the average time in seconds for the pain response of the animals in each group.

10

Table 7

Time in minutes after administration of analgesic	20	40
Time required in seconds for pain response:		
15 150 mg. per kg.	1 4.4	5.0
200 mg. per kg.	1 4.4	5.0

¹ Immediately prior to administration of analgesic.

It can be seen from Table 7 that the test compound of Example 9 possesses analgesic activity.

EXAMPLE 10

This example shows analgesic tests on rats by the tail flick test as described in Example 1. The tests were performed with the following nine compounds which were administered orally to rats.

Compound 1—1-(2,2-dimethyl-4-nitro-3-phenyl-cyclobutyl)piperidine
Compound 2—2,2-dimethyl-3-(1-piperidyl)-cyclobutane-1-carbonitrile
Compound 3—2,2-dimethyl-3-(1-piperidyl)-cyclobutylmethylamine
Compound 4—Cyclobutanecarbonitrile, 2-dimethylamino-3,3-dimethyl
Compound 5—N,N,2,2-tetramethyl-4-methylsulfonylcyclobutylamine
Compound 6—N,N,4,4-tetramethyl-2-phenyl-2-cyclobuteneamine
Compound 7—1,4-bis(4-methoxycarbonyl-2,2-dimethylcyclobutyl)piperazine
Compound 8—Methyl 3,3-diethyl-2-(1-piperidyl)cyclobutane-1-carboxylate
Compound 9—Secondary butyl 3,3-dimethyl-2-dimethylaminocyclobutane-1-carboxylate

The results of the test are given in Table 8 which shows the increase in analgesic effect over control values for each compound at various time intervals and also at various dosages. The dosages are expressed in milligrams of the active compound per kilogram weight of the animal. The time at which the animals were tested after the administration of the analgesic is given in Table 8. Values are also shown for aspirin and codeine which were run by the same method. The control value represents the time required for a tail flick by the rats when tested by the method of Example 1 but when no analgesic is given to the animal. The control value is about 4.3 seconds.

60

Table 8

Compound	Dose, mg./kg.	Time, minutes	Increase in analgesic effect over control values, seconds
65 1	200	20	0.8
2	150	5	1.2
3	75	20	1.6
4	20	40	0.6
5	300	20	1.1
6	50	20	1.8
7	300	20	1.2
8	300	20	1.0
9	300	20	2.2
Aspirin	200	20	0.4
Codeine	40	20	1.6

EXAMPLE 11

This example shows analgesic tests on rats by the tail flick test as described in Example 1. An oral dosage (100 mg./kg. of animal weight) of the hydrochloride salt of diethyl 3,3-dimethyl-4-diamethylaminocyclobutane-1,2-dicarboxylate was administered to rats. The results appear in Table 9. Each value given for the pain response is an average of seven tests (five animals per test).

Table 9

Time in minutes after administration of analgesic	5	10	15	20	40	60
Time required in seconds for pain response of animals tested	14.0	6.9	6.8	6.0	5.7	4.8

¹ Immediately prior to administration of analgesic.

It can be seen from Table 9 that the test compound of Example 11 possesses rapid analgesic activity.

The novel therapeutic compounds of this invention can be produced by a number of methods. Thus they can be produced by reacting a suitably substituted ketene, preferably in a polar solvent, with an unsaturated ester. The cyclic ketone so produced can be reduced to the alcohol, the alcohol converted into the bromide and the bromide treated with a suitable secondary dialkyl amine. A preferred method is by reacting enamines, such as those derived from secondary amines and aldehydes containing one alpha-hydrogen atom, with certain substituted olefins. This reaction can be illustrated by the following equation:

wherein X is a tertiary amine group having the nitrogen bonded directly to the unsaturated starting material, R₃ and R₄ are lower alkyl groups, R₅ is an electronegative group and R₆ is an electronegative group or hydrogen atom.

The molar proportion of the enamine reactant to the electronegative group-containing olefin reactant can be widely varied as the cyclobutane derivative product can be readily separated from excess or unreacted reactants. However, substantially stoichiometric amounts of the reactants are more generally utilized in accordance with usual chemical practice. Enamines such as N,N-dimethylisobutlenylamine react with equal molar proportions of such olefins as methyl acrylate as represented by the following equation:

One molar proportion of such enamines as 1,4-diisobutlenylpiperazine react in the present process with 2 molar proportions of such olefins as methyl acrylate as represented by the following equation:

The reaction of enamines and the substituted olefins to prepare the cyclobutane derivatives proceeds readily in the absence of added catalyst materials. The reaction can be conveniently effected by merely combining the reactants at room temperature. The olefinic compound reactants having nitro groups as the electronegative group are particularly reactive at ambient or even depressed temperatures in the present reaction. Reaction temperatures up to the decomposition of the reactants or the reaction product can be used, although reaction temperatures in the range of about 0° C. to 200° C. are more usually used, with elevated temperatures in the range of about 50° C. to 190° C. oftentimes utilized to facilitate the reaction. Typical reaction times vary from a few minutes to 20 hours depending mainly on the reaction temperature and the reactants employed. However, longer or shorter reaction periods can be utilized. The reaction is conveniently effected under atmospheric pressure, although higher pressures or even subatmospheric pressures can be utilized. The subject reaction can be effected in the absence of a solvent although a solvent that is substantially inert to the reactants and the reaction product can be utilized if desired.

The reaction of the described enamines and olefins containing electronegative groups proceeds in high yields to form the described cyclobutane derivatives. The cyclobutane derivative product can be worked-up or purified by conventional purification methods, the preferred method varying with the properties of the product. Particularly effective purification methods include fractional distillation under reduced pressure and fractional crystallization from solvents. However, other purification methods such as solvent extraction, chromatographic adsorption and the like can also be utilized.

The above described preferred method for making the compounds of this invention is illustrated by the following examples.

EXAMPLE 12

40 A mixture of N-isobutlenylpiperidine (69.5 g., 0.5 mole) and acrylonitrile (26.5 g., 0.5 mole) was heated in an autoclave for 2 hours at 175° C. Distillation of the reaction mixture gave 3.5 g. of acrylonitrile, 17 g. of N-isobutlenylpiperidine, and 59.5 g. (62% conversion) of 3,3-dimethyl-2-(1-piperidyl)cyclobutanecarbonitrile, B.P. 94-45 99° C. at 1.8-2.0 mm., N_D²⁰ 1.4780.

EXAMPLE 13

50 A mixture of N-isobutlenylpiperidine (139 g., 1.0 mole) and methyl acrylate (86 g., 1.0 mole) was heated in an autoclave for two hours at 180° C. Distillation of the reaction mixture gave, after removal of the unreacted methyl acrylate and N-isobutlenylpiperidine, 157 g. (70% conversion) of the methyl ester of 3,3-dimethyl-2-(1-piperidyl)cyclobutanecarboxylic acid, B.P. 103° C. at 3.7 55 mm., N_D²⁰ 1.4705.

EXAMPLE 14

60 To b-nitrostyrene (47.5 g., 0.32 mole) was added, N,N-dimethylisobutlenylamine (33 g., 0.33 mole). The mixture was stirred manually and the temperature rose to 92° C. over a two-minute period and then began to drop slowly. After about 15 minutes the reaction mixture crystallized. It was triturated with hexane and filtered to give 74.5 g. (94% yield) of crude N,N-dimethyl-2,2-dimethyl-3-phenyl-4-nitrocyclobutylamine, M.P. 86-91° C. On recrystallization from hexane the product melted at 90-92° C. Analysis showed 67.91% carbon, 8.34% hydrogen and 11.49% nitrogen as compared to calculated values of 67.72% carbon, 8.11% hydrogen 70 and 11.28% nitrogen.

EXAMPLE 15

75 Reacted as described in Example 14, a 0.32 mole portion of b-nitrostyrene and a 0.33 mole portion of N-isobutlenylpiperidine gave a substantially quantitative yield of 1-(2,2-

15

dimethyl-4-nitro-3-phenylcyclobutyl) piperidine, M.P. 70-72° C. Analysis showed 70.57% carbon, 8.52% hydrogen, and 9.67% nitrogen as compared to calculated values of 70.80% carbon, 8.39% hydrogen and 9.71% nitrogen.

EXAMPLE 16

A mixture of N,N-dimethylisobut enylamine (297 g., 3 moles) and methyl acrylate (258 g., 3 moles) was heated for two hours at 170° C. in an autoclave. Distillation of the reaction mixture gave, after removal of unreacted starting materials, 419 grams (75% yield) of the methyl ester of 3,3-dimethyl-2-dimethylaminocyclobutanecarboxylic acid (methyl 3,3-dimethyl-2-dimethylaminocyclobutane-1-carboxylate), B.P. 49-50° C. at 1.5 mm., n_D^{20} 1.4448.

EXAMPLE 17

A mixture of N,N-dimethylisobut enylamine (297 g., 3 moles) and acrylonitrile (159 g., 3 moles) was heated for two hours at 170° C. in an autoclave. Distillation of the reaction mixture gave, after removal of unreacted starting materials, 292 grams (64% yield) of 3,3-dimethyl-2-dimethylaminocyclobutanecarbonitrile, B.P. 44-45° C. at ca. 1 mm., n_D^{20} 1.4531.

EXAMPLE 18

A mixture of N,N-dimethylisobut enylamine (28 g., 0.283 mole) and methyl vinyl sulfone (28 g., 0.264 mole) was heated at atmospheric pressure. When the temperature reached 90° C., the mixture became homogeneous. The temperature was raised over a two-hour period to 160° C., and the reaction mixture was then distilled to give 49 grams (91% yield) of N,N-2,2-tetramethyl-4-methylsulfonylcyclobutylamine, B.P. 100-103° C. at 0.5-0.6 mm. The product crystallized in the receiver and melted at 85-86° C.

EXAMPLE 19

A mixture of N,N-dimethylisobut enylamine (82 g., 0.83 mole) and diethylmaleate (172 g., 1 mole) was heated under reflux for 18 hours, during which time the temperature of the mixture rose from 105° C. to 162° C. Distillation of the reaction mixture gave, after removal of unreacted starting materials, 150.5 g. (67% yield) of diethyl ester of 3,3-dimethyl-4-dimethylaminocyclobutane-1,2-dicarboxylic acid (diethyl 3,3-dimethyl-4-dimethylaminocyclobutane-1,2-dicarboxylate), B.P. 93-94° C. at 1.5 mm., n_D^{20} 1.4502.

EXAMPLE 20

A mixture of N-isobut enylpiperidine (208.5 g., 1.5 moles) and diethylmaleate (322.5 g., 1.87 moles) was heated at 150° C. for 5½ hours. Distillation of the reaction mixture gave, after removal of unreacted starting materials, 274 g. of the diethyl ester of 3,3-dimethyl-4-(1-piperidyl)cyclobutane-1,2-dicarboxylic acid, B.P. 113-120° C. at 1.0-1.5 mm., n_D^{20} 1.4663.

EXAMPLE 21

A one mole proportion of N-(2-ethyl-1-but enyl)piperidine was reacted with a one mole proportion of methyl acrylate for 2 hours at 170° C. in an autoclave. The resulting reaction product was distilled to separate the cyclobutane derivative, methyl 3,3-diethyl-2-(1-piperidyl)cyclobutanecarboxylate, B.P. 119-121° C. at 2 mm., n_D^{20} 1.4788.

EXAMPLE 22

A one mole proportion of 1,4-diisobut enylpiperazine and a two mole proportion of methyl acrylate were reacted for 2 hours at 170° C. in an autoclave. The resulting reaction product was triturated with hexane and filtered to give the cyclobutane derivative, 1,4-bis(4-methoxycarbonyl-2,2-dimethylcyclobutyl)-piperazine, M.P. 148° C.

16

EXAMPLE 23

A one mole proportion of N-isobut enylmorpholine was reacted with a one mole proportion of methyl acrylate for 2 hours at 170° C. in an autoclave. The resulting reaction product was distilled to separate the cyclobutane derivative, methyl 3,3-dimethyl-2-morpholinocyclobutane-carboxylate, B.P. 101-102° C. at 2.2 mm., n_D^{20} 1.4711.

EXAMPLE 24

10 A one mole proportion of N,N-di-n-butylisobut enylamine was reacted with a one mole proportion of methyl acrylate for 2 hours at 170° C. in an autoclave. The resulting reaction product was distilled to separate the cyclobutane derivative, methyl 3,3-dimethyl-2-di-n-butylamino-cyclobutanecarboxylate, B.P. 98° C. at ca. 1.5 mm., n_D^{20} 1.4543.

EXAMPLE 25

20 A one mole proportion of N,N-diisobutylisobut enylamine was reacted with a one mole proportion of methyl acrylate for 2 hours at 170° C. in an autoclave. The resulting reaction product was distilled to separate the cyclobutane derivative, methyl 3,3-dimethyl-2-diisobutylamino-cyclobutanecarboxylate, B.P. 93-100° C. at ca. 2 mm., n_D^{20} 1.4510.

25 Typical enamines used to prepare the present cyclobutane derivatives by the preferred method can be prepared by the methods described below.

EXAMPLE 26

30 The preparation of N,N-dibutyl isobut enyl amine was accomplished as follows. Isobut yraldehyde (180 g., 2.5 moles) was added over a ½-hour period to dibutylamine. The reaction mixture was then refluxed under a Dean-Stark trap for 12 hours during which time 30 ml. of water was collected. Fractional distillation of the mixture gave, after removal of low boilers, 228 g. (63%) of N,N-dibutylisobut enylamine, B.P. 70.5-72° C. at 4.5-5.2 mm., n_D^{22} 1.4409.

EXAMPLE 27

40 In a manner similar to that described in Example 26, isobut yraldehyde and diisobutylamine gave N,N-diisobutylisobut enylamine, B.P. 64° C. at 5.8 mm., n_D^{20} 1.4375, in 57% yield.

EXAMPLE 28

45 In a manner similar to that described in Example 26, cyclohexanecarboxaldehyde and piperidine gave 1-cyclo-50 boxyldenemethyl piperidine, B.P. 88° C. at 3 mm., n_D^{20} 1.5042, in 85% yield.

EXAMPLE 29

55 In a manner similar to that described in Example 26, 2-ethylbutyraldehyde and piperidine gave N-(2-ethyl-1-but enyl)piperidine, B.P. 103-110° C. at 37-45 mm., n_D^{20} 1.4693, in 87% yield.

EXAMPLE 30

60 Over a 2-hour period isobut yraldehyde (400 g., 5 moles) was added to piperazine (172 g., 2 moles) at 35-40° C. The mixture was stirred and refluxed under a Dean-Stark trap for 7 hours, during which time 74 ml. of water was collected. Distillation of the reaction mixture gave, after removal of low boilers, 221 g. (57%) of 1,4-diisobut enyl piperazine, B.P. 70-75° C. at 2 mm., M.P. 35-37° C.

EXAMPLE 31

65 A chilled mixture of isobut yraldehyde (288 g., 4 moles), 500 ml. of xylene and 150 g. of anhydrous potassium carbonate was charged to an autoclave. Then dimethylamine (200 g., 4.4 moles) was added and the autoclave was closed and heated at 100° C. for 4 hours. The autoclave was allowed to cool, was vented cautiously and discharged. The mixture was filtered by gravity and

the filtrate was distilled to give after removal of unreacted starting materials, 198 g. (50%) of N,N-dimethyl-isobutylamine, B.P. 87-89° C., n_D^{20} 1.4219.

This application is a continuation-in-part of our co-pending application Serial No. 825,648, filed on July 8, 1959, now abandoned.

What is claimed is:

1. An analgesic composition in unit dosage form comprising a significant quantity of a pharmaceutical carrier and from about 0.1 grain to about 25 grains of a member selected from the group consisting of a cyclobutane derivative and a non-toxic acid addition salt of said cyclobutane derivative wherein the cyclobutane derivative can be represented by the following generic formula:

wherein each of A and A' is a lower alkyl radical; each of R, R¹, R² and R³ is a member selected from the group consisting of hydrogen, a lower alkyl radical, the phenyl radical, the nitro radical, a lower alkyl sulfonyl radical, the cyano radical, a lower alkyl ester, and a lower alkyleneamino radical, provided that at least one of R, R¹, R² and R³ is the phenyl, the nitro, a lower alkyl sulfonyl, the cyano, a lower alkyl ester, and a lower alkyleneamino radical; R⁴ is a member selected from the group consisting of hydrogen and a lower alkyl radical having from 1 to 2 carbon atoms; and X is tertiary amino radical selected from the group consisting of a lower dialkylamino, the piperazino, the piperidino, the morpholino, and the thiomorpholino radical.

2. An analgesic composition in unit dosage form comprising a significant quantity of a pharmaceutical carrier and from about 0.1 grain to about 25 grains of a cyclobutane derivative having the following generic formula:

wherein each of A and A' is a lower alkyl radical having from 1 to 2 carbon atoms, R¹ and R² is a carbalkoxy radical having from 1 to 3 carbon atoms in each alkoxy chain; and X is a dialkylamino radical having from 1 to 2 carbon atoms in each alkyl chain.

3. An analgesic composition in unit dosage form comprising a significant quantity of a pharmaceutical carrier and from about 1 to about 10 grains of a non-toxic acid addition salt of diethyl 3,3-dimethyl-4-dimethylaminocyclobutane-1,2-dicarboxylate.

4. An analgesic composition in unit dosage form comprising a significant quantity of a pharmaceutical carrier and from about 1 to about 10 grains of a non-toxic acid addition salt of methyl 3,3-dimethyl-2-dimethylaminocyclobutane-1-carboxylate.

5. An analgesic composition in unit dosage form comprising a significant quantity of a pharmaceutical carrier and from about 1 to about 10 grains of a non-toxic acid addition salt of methyl 2,2-dimethyl-3-piperidinocyclobutane-1-carboxylate.

6. An analgesic composition in unit dosage form comprising a significant quantity of a pharmaceutical carrier and from about 1 to about 10 grains of a non-toxic acid addition salt of N,N,2,2-tetramethyl-4-methylsulfonylcyclobutylamine.

7. An analgesic composition in unit dosage form comprising a significant quantity of a pharmaceutical carrier and from about 1 to about 10 grains of a non-toxic acid addition salt of 2,2-dimethyl-3-(1-piperidyl)cyclobutane-carbonitrile.

8. An analgesic composition comprising from about 1 to about 10 grains of a member selected from the group

consisting of diethyl 3,3-dimethyl-4-dimethylaminocyclobutane 1,2-dicarboxylate and a non-toxic acid addition salt thereof, and aspirin in a quantity varying from about 0.25 to 4 times the quantity of said cyclobutane derivative.

5 9. A method for inducing analgesia which comprises administering to an animal, including a human, an analgesically effective quantity of a member selected from the group consisting of a cyclobutane derivative and a non-toxic acid addition salt of said cyclobutane derivative wherein the cyclobutane derivative can be represented by the following generic formula:

wherein each of A and A' is a lower alkyl radical; each of R, R¹, R² and R³ is a member selected from the group consisting of hydrogen, a lower alkyl radical, the phenyl radical, the nitro radical, a lower alkyl sulfonyl radical, the cyano radical, a lower alkyl ester, and a lower alkyleneamino radical, provided that at least one of R, R¹, R² and R³ is the phenyl, the nitro, a lower alkyl sulfonyl, a lower alkyleneamino, the cyano and a lower alkyl ester radical; R⁴ is a member selected from the group consisting of hydrogen and a lower alkyl radical having from 1 to 2 carbon atoms; and X is a tertiary amino radical selected from the group consisting of a lower dialkylamino, the piperazino, the piperidino, the morpholino, and the thiomorpholino radical.

20 10. A method for inducing analgesia which comprises administering to an animal, including a human, an analgesically effective quantity of a cyclobutane derivative having the following generic formula:

wherein each of A and A' is a lower alkyl radical having from 1 to 2 carbon atoms; R¹ and R² is a carbalkoxy radical having from 1 to 3 carbon atoms in each alkoxy chain; and X is a dialkylamino radical having from 1 to 2 carbon atoms in each alkyl chain.

25 11. A method for inducing analgesia which comprises administering to an animal, including a human, from about 1 to about 10 grains of a non-toxic acid addition salt of diethyl 3,3-dimethyl-4-dimethylaminocyclobutane-1,2-dicarboxylate.

30 12. A method for inducing analgesia which comprises administering to an animal, including a human, from about 1 to about 10 grains of a non-toxic acid addition salt of methyl 3,3-dimethyl-2-dimethylaminocyclobutane-1-carboxylate.

35 13. A method for inducing analgesia which comprises administering to an animal, including a human, from about 1 to about 10 grains of a non-toxic acid addition salt of N,N,2,2-tetramethyl-4-methylsulfonylcyclobutylamine.

40 14. A method for inducing analgesia which comprises administering to an animal, including a human, from about 1 to about 10 grains of a non-toxic acid addition salt of 2,2-dimethyl-3-(1-piperidyl)cyclobutanecarbonitrile.

45 15. A method for inducing analgesia which comprises administering to an animal, including a human, from about 1 to about 10 grains of a cyclobutane derivative selected from the group consisting of diethyl 3,3-dimethyl-4-dimethylaminocyclobutane 1,2-dicarboxylate and a non-toxic acid addition salt thereof and aspirin, the quantity of aspirin being about 0.25 to 4 times that of the cyclobutane derivative.

50 16. A method for inducing analgesia which comprises

administering to an animal, including a human, an analgesically effective quantity of a cyclobutane derivative selected from the group consisting of diethyl 3,3-dimethyl-4-dimethylaminocyclobutane 1,2-dicarboxylate and a non-toxic acid addition salt thereof and codeine.

17. A method for inducing analgesia which comprises administering to an animal, including a human, an analgesically effective quantity of a non-toxic acid addition salt of methyl 2,2-dimethyl-3-piperidinocyclobutane-1-carboxylate.

18. A method for inducing analgesia which comprises administering to an animal, including a human, an analgesically effective quantity of a non-toxic acid addition salt of 1-(2,2-dimethyl-4-nitro-3-phenylcyclobutyl)piperidine.

19. A method for inducing analgesia which comprises administering to an animal, including a human, an analgesically effective quantity of a non-toxic acid addition salt of 2,2-dimethyl-3-(1-piperidyl)-cyclobutylmethylamine.

20. A method for inducing analgesia which comprises administering to an animal, including a human, an analgesically effective quantity of a non-toxic acid addition salt of 2-dimethylamino-3,3-dimethylcyclobutanecarbonitrile.

21. A method for inducing analgesia which comprises administering to an animal, including a human, an analgesically effective quantity of a member selected from the group consisting of bis(4-methoxycarbonyl-2,2-dimethylcyclobutyl)-piperazine and a non-toxic acid addition salt thereof.

22. A method for inducing analgesia which comprises administering to an animal, including a human, an analgesically effective quantity of a non-toxic acid addition salt of methyl 3,3-dimethyl-2-morpholinocyclobutane-1-carboxylate.

23. A method of inducing analgesia which comprises administering to an animal, including a human, an analgesically effective quantity of a member selected from the group consisting of 2-(thiomorpholino)-2-ethyl-3-

ethyl 3-methyl-4-methyl-4-cyano-1-carb-secondary butoxy-cyclobutane.

24. A method for inducing analgesia which comprises administering to an animal, including a human, an analgesically effective quantity of a non-toxic acid addition salt of diethyl 3,3-dimethyl-4-(1-piperidyl)cyclobutane-1,2-dicarboxylate.

25. An analgesic composition in unit dosage form comprising a significant quantity of a pharmaceutical carrier and from about 0.1 of a grain to about 25 grains of a cyclobutane derivative of the formula:

15

wherein each of A and A' is an alkyl having from 1 to 2 carbon atoms; R² is a carbalkoxy radical having from 1 to 3 carbon atoms in the alkoxy portion; and X is a dialkylamino radical having from 1 to 2 carbon atoms in each alkyl chain.

26. A method for inducing analgesia which comprises administering to an animal, including a human, an analgesically effective quantity of a cyclobutane derivative of the formula:

30

wherein each of A and A' is an alkyl having from 1 to 2 carbon atoms; R² is a carbalkoxy radical having from 1 to 3 carbon atoms in the alkoxy portion; and X is a dialkylamino radical having from 1 to 2 carbon atoms in each alkyl chain.
